PRESSURE REGULATING SYSTEM

David Gregg, Caldwell, N. J., assignor to Bendix Aviation Corporation, South Bend, Ind., a corporation of Delaware

Application April 18, 1940, Serial No. 330,385

14 Claims. (Cl. 123—119)

The present invention relates to the subject of pressure regulation and more particularly to the regulation of pressure of the fuel and air mixture in the intake of an internal combustion engine.

Internal combustion engines for aircraft are subject to a wide range of input pressures, particularly due to the wide range of altitude traversed in normal flight, and also because of the variation in pressure which is the result of non-uniform supercharger action.

In the past, attempts have been made to regulate the supercharger, both manually and automatically, but none of these attempts, up until the present invention, have been successful in producing a thoroughly reliable and simple automatic device for the regulation of intake pressures.

One of the objects of the present invention lies in the provision of a pressure regulator for automatically maintaining, over a wide limit of intake pressure variations, a constant manifold pressure in an internal combustion engine.

Another object of the present invention resides in the provision of a regulator, in a system subject to pressure variation, that will automatically maintain a preset pressure through a novel pressure sensitive and servo-motor system.

Other objects of the invention include the provision of a pressure regulating system, which is set into operation by manipulation of the conventional hand throttle and which employs a novel servo-motor system for maintaining manifold pressure constant, and also, the provision of a novel means in an automatic pressure regulating system for permitting the operator to override or overpower the servo-system merely by manipulation of the hand throttle.

Other objects of the present invention will appear from the following specification when studied in conjunction with the attached drawing, in which there is shown, partly in cross-section and partly schematic, a pressure regulating system of the present invention as applied to the input manifold of an internal combustion engine.

The present invention, as applied to internal combustion engines, particularly those adapted for use on aircraft, includes the conventional throttle valve and hand throttle control to which is applied a servo-motor actuated by a suitable pressure source, such as the oil pump of an engine, which motor is under the control of a novel mechanism responsive to changes in manifold pressure. Thus, when a pilot sets his hand throttle to obtain a desired manifold pressure

and releases the hand throttle, the device of the present invention will automatically vary the throttle for changing input pressures in order to maintain the manifold at the present value. Further, if the pilot desires to change the manifold pressure at any time, he may accomplish this end by merely moving the hand throttle to the position which gives his his newly desired manifold pressure, and upon release of the hand throttle, this new pressure will be automatically maintained by the novel device of the present invention, which is described below.

The intake manifold is shown generally at 10, at one end of which is a conventional carburetor 11 having an air intake scoop 12 and a fuel mixing chamber 13. A throttle valve 14, of conventional design, is disposed within manifold 10 and is connected through a suitable linkage 15 to a hand throttle lever 16. A supercharger 17 is connected in manifold 10 at some point posteriorly of carburetor 11. Engine manifold 10 connects to a conventional aircraft engine, not shown. Supercharger 17 is driven through a suitable gear system 19 by means of the aircraft engine.

At the pilot's position there is provided a manifold pressure gauge 20 of any ordinary design, which is connected to manifold 10 by tubular conduit 21. A servo-motor 22, which includes a cylinder 23, a piston 24, and a piston rod 25, is connected directly as shown, by means of any suitable linkage, to hand throttle 16. This servo-motor is preferably actuated by oil pressure from the internal combustion engine, from which oil is led into servo-motor 22 through a suitable conduit 26. Movement of piston 24 is controlled by valves 27 and 28, rigidly linked together by bar member 29 to form a two-way valve system. With valves 27 and 28 positioned as shown in the drawing, oil from conduit 24 is introduced to cylinder 23 through port 30 which has been uncovered by movement of valve 28 to the right of its neutral position directly over port 30. The pressure of oil through this port will force piston 24 to move to the left, forcing oil out of cylinder 23 through port 31 and into an oil sump, not shown, through drain port 32. Movement of servo-motor to the left, will cause hand throttle 16 to move to the left, opening throttle member 14 and increasing the manifold pressure.

It will be readily seen that movement of valve 27 to the left of its neutral position, directly above port 31, will cause oil under pressure to be introduced into cylinder 23 through port 31, forcing piston 24 to move to the right, simultaneously discharging oil through port 31 and to

the oil sump, not shown, through port 33. Upon movement of piston 24 to the right, hand throttle 16 will be moved to the right, tending to close throttle valve 14 and effect a reduction in the manifold pressure.

When servo-motor 22 moves hand throttle 16, the latter member is pivoted about point 34. Upon manual movement of hand throttle lever 16, however, the first pivotal point is at 35, at which point piston rod 25 is loosely connected by means of a pin to lever 16. Rotation of lever 16 about point 35 causes point 34 to be advanced through an arc limited by the movement of block 36 in the housing 37. As shown in the drawing, hand throttle member 16 is in a position indicating that the hand throttle 16 has been pulled to the right and that the pilot or operator is still pulling the hand throttle to the right. This is evidenced by the fact that block 36 has been moved against the action of coil spring 38 into abutting relation with the left-hand wall of housing 37. When hand throttle 16 is not being manually moved, block 36 assumes a neutral position, with its end-faces equi-distantly spaced from the left and right end-walls of housing 37, and springs 38 and 39 will be under equal tension, tending to maintain block 36 in such neutral position. Block 36 has rigidly attached thereto, a rod member 40, carrying three valve members 41, 42 and 43, rigidly spaced along the length of rod member 40.

When lever member 16 is not being manually operated, valve members 41, 42 and 43 assume positions directly over the openings of passageways 44 and 45, maintaining these passageways closed. However, in the position shown, valve member 41 has been moved to the left of the opening of passageway 44 and permits communication of oil to both sides of piston 24. The drawing shows that servo-motor 22 is out of control, since any oil admitted to cylinder 23, through either of ports 30 and 31, will be immediately by-passed around piston 24. In this condition, operation of throttle lever 16 is permitted without interference of the servo-motor 22.

Simultaneously with the disabling or overpowering of servo-motor 22 oil is permitted to flow, under manifold pressure, from a reservoir 46 which communicates through a conduit 47 with intake manifold 10. Oil passes from reservoir 46 through tubular conduit 48 and through passageway 49 into conduit 50, which communicates with the cylindrical chamber 51, having therein a piston 52 and piston rod 53.

Housing 54 contains a flexible, metal chamber 55, having a corrugated shell or body portion, such as a "Sylphon," having sealed end-walls and partitions 56 and 57. Chamber 55 is secured to the wall of housing 54 by any conventional means, such as a nut and bolt 58, as shown. Chamber 55 may be sealed at any desired pressure, but preferably under a vacuum, and within the chamber is a coiled spring 59 which tends to expand the walls of chamber 55 and increase the effective pressure at which the chamber is sealed, for a purpose to be described later. End-wall 57 also acts as an end-wall or partition for another chamber which comprises a flexible, corrugated, metallic shell member 61, such as a "Sylphon" bellows. The end opposite partition 57 is connected to end-wall 62, in any conventional manner, such as by welding, to make the connection fluid-tight. Piston rod 53 extends into chamber 61 and is surrounded by a packing

member 64, which maintains a fluid-tight seal about piston rod 53. By means of a connector, such as screw 65, a coiled spring 66 is attached to end-wall 57 and the other end of spring 66 is connected to the extremity of piston rod 53. End-wall or partition 57 is provided with an arm 67, which is connected to a rigid link member 68 by means of any conventional hinge connection 69. Link member 68 is securely fastened to bar member 29.

Chamber 61 has an aperture 70 to which is affixed a conduit 71 communicating with intake manifold 10 at point 72.

The pressures within the three chambers 55, 51, and 61 are such that at any arbitrary manifold pressure desired, the system is in complete balance, that is, there is no movement of partition 57, and thus, valves 27 and 28 are in their normal position sealing ports 31 and 30, respectively. In this balanced condition, the effective pressure within chamber 55 is due to the combined effect of the gas pressure within chamber 55, and the mechanical force exerted by coil spring 59. If chamber 55 is completely evacuated, then the effective pressure is solely that exerted by spring 59. To this pressure there is added an adjustable pressure element, namely, a coil spring 66 having a tension value which, depending upon the position of piston 52 in chamber 51, will aid the effective pressure in chamber 51 and tend to draw end-wall or partition 57 to the right. However, with the same manifold pressure in chamber 61 that exists in chamber 51, when the latter is sealed, movement of partition 57 to the right is prevented, and the tension of spring 66 is sufficient to hold end-wall 57 from moving to the left, thus acting to keep valves 27 and 28 closed. When, however, a certain manifold pressure has been introduced to chamber 51, passageway 45 is closed by means of valves 42 and 43. Any change of manifold pressure will be reflected in chamber 61, which is continuously open to manifold pressure, and if manifold pressure decreases, end-wall 57 will move to the right, carrying valves 27 and 28 to the right of ports 31 and 30, respectively, as shown in the drawing, allowing oil from the engine pump to be introduced through port 31 into cylinder 23 and move hand lever 16 to the left. This action will, in turn, tend to open throttle valve 14 and restore the preset manifold pressure to chamber 61. If, however, the manifold pressure in chamber 61 increases over that in chamber 51, wall 57 will move to the left and cause valves 27 and 28 to move to the left of ports 31 and 30, respectively, admitting oil under pressure into cylinder 23 through port 31 and forcing piston 24 to move to the right, closing throttle valve 14 and decreasing the manifold pressure by an amount sufficient to reestablish the original pressure set in chamber 61.

Any manifold pressure which the pilot chooses, by manipulation of lever 16, can be maintained automatically by the balancing of pressures in chambers 51, 55, and 61, in the manner above described, so that automatically, any variation in chamber 61 from the established pressure in chamber 51 will cause movement of wall 57 and consequent operation of servo-motor 22 to restore the intake manifold to the pressure set in chamber 51. In accordance with the present invention, therefore, the pilot always has control of manifold pressure and throttle valve setting, and the desired manifold pressure is automatically maintained, yet no override or lock-out

positions for the throttle lever, or any second lever, are necessary, as the pilot may instantly overpower the servo-motor and the rest of the automatic system by mere manipulation of the throttle lever 16.

While only one embodiment of the invention has been shown and described, it is apparent that numerous changes may be made without exceeding the scope of the invention. For example, it has been stated that the servo-motor 22 is actuated by oil from the conventional engine pump. Obviously, any source of electrical energy, or of fluid pressure available may be utilized. Further, while supercharger 17 is shown as part of the system, and while the description makes reference to the regulation of supercharger pressure, it is obvious that the novel invention of the present system is useful with an intake manifold not having provision for supercharging, and also, the pressure regulation system of the present invention may be used to regulate fluid pressures other than intake pressures of internal combustion engines. By means of the present invention, the fluid pressure in any conduit carrying a liquid or gas can be automatically regulated. Engine manifold pressure can, of course, be regulated by controlling the speed of the supercharger, or by varying valves placed at the input and the output of the supercharger, as well as by governing the movement of a carburetor throttle valve. The invention is not restricted, therefore, to the particular drawing and description chosen to represent one embodiment thereof, and it is not intended that the invention be limited by the description and drawing, but solely by the scope of the appended claims.

What is claimed is:

1. In a regulator of manifold pressure for internal combustion engines, an intake manifold, a throttle valve in said intake manifold, a hand throttle for moving said throttle valve, a servo-motor for controlling the movement of said hand throttle, valve means associated with said hand throttle to effect overpowering of said servo-motor, a multiple pressure chamber device having one chamber open to manifold pressure, a second chamber sealed at a predetermined pressure, a third chamber selectively open and closed to manifold pressure, said third chamber, when closed, cooperating with said second chamber to balance the pressure of said first chamber and when open to create a balance at a different pressure, valve means associated with said multiple chamber pressure device to actuate said servo-motor during periods of pressure unbalance to vary the opening of said throttle valve and thereby maintain the manifold pressure constant regardless of changes in manifold pressure due to conditions other than throttle valve setting.

2. In combination with the intake manifold of an internal combustion engine, a throttle valve therein, a manually operable member for setting said throttle valve, a servo-motor connected to control movement of said manually operable member, means initiated by manual movement of said manually operable member to overpower said servo-motor and to restore said servo-motor upon cessation of manual movement of said member, a first pressure chamber open to manifold pressure, a second pressure chamber sealed at a predetermined pressure, a third pressure chamber selectively open and closed to manifold pressure, means connected between said first and

third chambers to balance the pressure in said second pressure chamber when said third pressure chamber is open to manifold pressure, and valve means for operating said throttle valve through said servo-motor upon change of manifold pressure during intervals when said third chamber is closed to manifold pressure, whereby a predetermined manifold pressure will be maintained regardless of the tendency of manifold pressure to change due to conditions other than throttle valve setting.

3. In a pressure regulating system wherein a predetermined pressure may be manually set and automatically maintained, a fluid conduit in which the pressure is to be maintained, a valve therein, manual means for adjusting said valve to obtain the desired pressure, a servo-motor for adjusting said valve through said manual means, means responsive to the manual adjustment of said valve for overpowering said servo-motor and for restoring said servo-motor upon cessation of manual operation, and pressure responsive means having a chamber open to conduit pressure, for operating said servo-motor to adjust said valve and restore the pressure in said conduit to its predetermined value.

4. In a pressure regulating system, a conduit, the pressure of which is to be regulated, a first valve therein, a mechanism including both automatic and manual means for adjusting the pressure of said conduit through said valve, said automatic means including a servo-motor connected to said valve, a first chamber open to conduit pressure, a second chamber sealed at a predetermined pressure, a third chamber having means for effecting mechanical balancing of said first and second chambers at desired conduit pressures, a second valve associated with said chambers so as to be movable between conditions of mechanical balance to operate said first valve through said servo-motor and maintain the pressure of said conduit constant, and said manual means including a hand lever connected through suitable linkage to said first valve and having means operable upon manipulation thereof to overpower said automatic means.

5. In combination with the intake manifold of an internal combustion engine, a supercharger, means for regulating the pressure delivered thereby to said manifold, comprising a throttle valve, a throttle lever for adjusting said valve, a servo-motor connected to said valve through said throttle lever, means responsive to changing manifold pressure to operate said servo-motor and said throttle valve to restore the desired manifold pressure, and means connected to said throttle lever to overpower said servo-motor and permit a change of manifold pressure by manual operation of said throttle lever.

6. In a system for automatically regulating the fluid pressure in a conduit and for manually setting desired pressures, a conduit, a valve therein for adjusting the pressure in the conduit, a lever associated with said valve, a servo-motor connected to said lever, and means actuated by manual operation of said lever to disable said servo-motor and upon cessation of manual operation to restore control of said lever to said servo-motor, whereby any manually selected conduit pressure will be automatically maintained.

7. In combination with the intake manifold of an internal combustion engine, a pressure throttling member within said manifold, a manual adjuster of said member connected thereto, a servo-motor for operating said manual ad-

juster, means responsive to changes in manifold pressure for adjusting said pressure throttling member through said servo-motor and means associated with said manual adjuster and responsive to manual adjustment thereof to disable said servo-motor, whereby a desired manifold pressure may be selected, and automatically maintained.

8. In combination with the intake manifold of an internal combustion engine, a member for throttling the pressure within said manifold, means for adjusting said member, a servo-motor for controlling said means, a mechanism responsive to changes in manifold pressure for adjusting said member through said servo-motor, and means associated with the first-named means for disabling said servo-motor and enabling a manifold pressure to be set independently of said servo-motor.

9. In combination with the intake manifold of an internal combustion engine, a regulator of supercharger pressure, comprising a throttle valve in said manifold, a lever connected thereto, a servo-motor adapted to control said throttle valve through said lever, a first pressure chamber open to manifold pressure, a second pressure chamber, sealed at a desired pressure, said chambers having flexible walls with a common end-wall movable under conditions of unbalance between the pressures in said first and second chambers, a third chamber having rigid walls and an opening in one wall, a piston within said chamber, a piston rod connected thereto and extending through the opening in said wall and into said first chamber, a packing member about said piston rod adapted to seal said third chamber, a spring member connected to said end-wall and to said piston rod, a two-way valve connected to said end-wall and movable during changes in manifold pressure to operate said servo-motor, and means actuated by manual operation of said lever to overpower said servo-motor and to open said third chamber to manifold pressure, said means, upon cessation of manual operation of said lever, acting to restore control to said servo-motor and to seal said third chamber at manifold pressure, whereby any changes in manifold pressure will unbalance the pressures in said chambers and actuate said servo-motor through said two-way valve.

10. In combination with the intake manifold of an internal combustion engine, a regulator of manifold pressure including a throttle valve, a hand lever connected to said throttle valve, a servo-motor connected through suitable linkage to said hand lever, a two-way valve capable of urging the servo-motor to increase or decrease manifold pressure through control of said throttle valve, and means for controlling the operation of said two-way valve, said means including an element connected to said two-way valve, a flexible chamber open to manifold pressure, a flexible compartment sealed at a predetermined pressure and a connection common to said flexible compartment and said flexible chamber and to said two-way valve for governing operation of said servo-motor.

11. A regulator of manifold pressure for internal combustion engines, comprising a housing, a first pressure chamber therein sealed at a predetermined pressure value and having a tubular, flexible shell, a second chamber having a tubular, flexible shell, a common end-wall between said chambers, said second chamber being open to manifold pressure, a third chamber having a rigid shell member, valve means for opening and closing communication of said third chamber to manifold pressure, a piston within said third chamber, a piston rod extending from said piston through a fluid-tight seal into said second chamber, resilient connecting means interposed between said common end-wall and said piston rod, said common end-wall being movable when the effective pressures in said first and second chambers are unequal, the pressure in said third chamber being additive to that in said first chamber to balance the pressure in said second chamber at different manifold pressures, and means responsive to movement of said common end-wall during intervals of pressure unbalance to rebalance said pressures.

12. In a device for regulating fluid pressure, a housing having a first chamber sealed at a fixed pressure and having a flexible element, a second chamber open to the pressure to be regulated and having a flexible element connected to said first chamber, a third chamber selectively sealed at any desired fluid pressure within working range of the device, means common to said first and third chambers to balance the pressure in said second chamber, a servo-motor adapted to be connected to a pressure regulating valve, and means associated with said flexible elements of said first and second chambers to control the operation of said servo-motor.

13. A regulator of intake manifold pressure for an internal combustion engine including a throttle valve actuating member, a servo-motor connected thereto, means responsive to changing manifold pressure for operating said servo-motor to maintain the manifold pressure constant, and means operable upon manual movement of said throttle valve actuating member for disabling said servo-motor and for restoring said servo-motor upon cessation of manual movement of said member.

14. In a regulator of manifold pressure, a servo-motor having a hand throttle engaging member and a source of energization, valve means for controlling the action of said servo-motor, a chamber having a port for communication with a manifold and a movable element connected to said valve means, means subject to changing manifold pressure for moving said valve means and operating said servo-motor, said last-named means being operative upon changes in manifold pressure to return the manifold pressure to its desired value, and a hand throttle operated means associated with said servo-motor for disabling said servo-motor upon operation thereof.

DAVID GREGG.
